VALVE MECHANISM FOR GAS METERS

Application filed November 26, 1927, Serial No. 235,770, and in Germany December 1, 1926.

My present invention relates to a valve mechanism for gas meters, particularly those of the type known as dry gas meters. The object of my improvements is to simplify the construction of the valve mechanism and to reduce the chances of leakage. Other features of the invention will appear from the description following hereinafter and from the accompanying drawings, which illustrate three typical and satisfactory forms of my present invention, and in which

Fig. 1 is a horizontal section through one embodiment of my invention; Fig. 2 is a partial vertical section on the line 2-2 of Fig. 1; Fig. 3 is a diagrammatic plan view of another embodiment of my invention; Fig. 4 is a similar view of a third form.

The casing of the gas meter illustrated by Figs. 1 and 2 has a horizontal partition or wall 1 below which are located the measuring chambers 2, 3, 4, and 5 through which flows the gas to be metered; these chambers may be of the usual diaphragm type, or of any other suitable construction, and I have therefore not deemed it necessary to show them in detail in the drawings. Suffice it to say that the movable members of such measuring chambers impart an oscillating motion to the two upright rock shafts 6 and 7 which extend through the partition and which, by means of crank arms 8, 9 and connecting rods 10, 11 respectively, are adapted to rotate the valve-controlling shaft 12. This shaft is shown as provided with cranks 23, 24 set at 90° to each other, the crank 23 being connected with a rod 25 arranged to actuate a slide valve 21 which reciprocates in the direction indicated by the arrows and controls two ports 13 and 15, for instance the inlet ports leading from the inlet chamber 28 of the casing to two different measuring chambers. The valve 21 moves in unison with a pin 46 which, by means of a rod 47 extending beneath the partition 1, and within one of the measuring chambers, imparts a like reciprocating motion to another slide valve 45, controlling ports 14, 16, which in the case assumed above will be the outlet ports from the same measuring chambers that have the inlet ports 13 and 15 respectively. The ports 14, 16 open into

the outlet chamber 29, which is separated from the inlet chamber 28 by a transverse vertical partition 27. Fig. 1 also shows another pair of inlet ports 17, 19 and another pair of outlet ports 18, 20 companion to the ports 17, 19 respectively, these ports 17, 19 and 18, 20 being controlled by slide valves exactly like the slide valves 21, 45, the crank 24 actuating the valves of the ports 17, 19, 18, 20 in the same manner that the valves 21, 45 are actuated by the crank 23; that is, the crank 24 actuates the valve controlling the ports 17, 19 directly, by means of a rod corresponding to the rod 25, while the valve controlling the ports 18 and 20 would be actuated from the crank 24 indirectly, by means of a connection of the same character as the connection 46, 47, 48, the latter numeral designating a pin similar to the pin 46 and connected with the slide valve 45. Of course, as the cranks 23, 24 are placed at 90° from each other, the slide valves 21, 45 will be timed differently from the slide valves of the other pair. The ports controlled by the slide valves are preferably of two different types, the ports 13, 14, 19, and 20 being shown as having, at the ends adjacent to the companion ports 15, 16, 17, and 18 respectively, extensions or slits ranging longitudinally, the pins such as 46 and 48 traveling in these slits. The necessity for these slits arises from the fact that the stroke of the slide valves and of the pins is greater than the width of the ports, measured in the direction in which the valves move. Said slits, however, should not act to increase the effective area of the respective ports, and are therefore permanently closed or covered, either by the body of the valve (as shown for the valve 21 in Fig. 1), or by a tongue projecting from the valve body, as shown in Fig. 1 for the tongue 49 extending from the valve 45 toward the companion valve 21. This tongue may also be utilized for guiding the valve in a rectilinear path during its reciprocating movement. I have not indicated any separate guides engaging the valves, as these expedients will be readily understood and provided by persons skilled in this art. In fact, the pins 46, 48 may be guided in the slit extensions of the ports 13, 14, 19, and 20.

and 14 respectively effectively enough to insure a rectilinear movement of the valves, without any additional guides.

It will be seen that the valve motion described above is exceedingly simple, composed of a very small number of parts, efficient in operation, with a minimum of surfaces exposed to wear, and with practically no danger of leakage and consequent inaccuracy of measurement. In particular, it will be noted that the connection by which the motion of the shaft 12 (located in the compartment 28) is transmitted to the valve 45 (located in the compartment 29) does not pass through the partition 27 which separates the two compartments 28 and 29, but extends beneath the partition 1; I thus avoid the difficulty of obtaining a tight joint experienced when, as in certain prior constructions, the actuating connection to one valve of each pair extends through a partition such as 27. It will further be noted that both shafts 6 and 7 and their connections with the shaft 12 are located in the same chamber (28), thus avoiding the danger of leakage which exists when, as in certain prior constructions, the shafts such as 6 and 7 are on opposite sides of the partition 27 so that one of the shaft-operating rods such as 10, 11 has to extend through said partition.

In the embodiment of my invention illustrated by Fig. 3, I have shown a shaft 12' rotated in any well-known or approved manner by the movable members of the measuring chambers; this shaft, therefore, corresponds in function to the shaft 12 of Figs. 1 and 2. On the shaft 12' is secured a toothed wheel 51, in mesh with a toothed wheel 52 of like diameter, and with a similar toothed wheel 53. Said wheels 52, 53 are provided with crank pins 54, 59 respectively extending downwardly into recesses 57, 58 provided in the upper surfaces of the slide valves 21', 21^a respectively; of these, the valve 21' controls two ports corresponding to the ports 13, 15 of Fig. 1, while the valve 21^a controls two ports corresponding to the ports 17 and 19 of Fig. 1. The valves 21', 21^a are guided by any suitable means 68 for rectilinear movement in the direction indicated by the arrows. Both valves and their actuating parts 51, 52, 53, 54, 59 are located in the same compartment (compartment corresponding to 28 of Figs. 1 and 2), so that in connection with these parts, there are no joints liable to leak. The lower end surfaces of the pins 54, 59 do not engage the respective valves, the contact being exclusively at the peripheral surfaces of said pins; this is done for the purpose of reducing friction and wear. The outline of each of the recesses 57, 58 consists of circular arc portions *a*, *b*, the radius of which is equal to the eccentricity of the crank pins 54, 59, the centers of said arcs lying on the axial line *c*—*c* extending through the center

of the wheel 52 or 53 respectively; furthermore, the outline of each of said recesses includes short transverse extensions *d* located at the junction of the arc portions *a*, *b* of the same recess. It will be obvious that with the wheels 51, 52, 53 rotating in the direction indicated by the arrows (at the same angular speed, in view of the equal size of said wheels), the pins 54, 59 will cause a reciprocation of the slide valves 21', 21^a in the direction of the arrows, and it will further be obvious that, owing to giving the arcs *a*, *b* radii equal to the eccentricity of the crank pins 54, 59, the slide valve will be given a period of rest or dwell at the end of each stroke, during the time that the said pins travel along one-half of the respective arc *a* or *b*. While Fig. 3 shows only two valves, for controlling ports such as the ports 13, 15, 17, and 19 of Fig. 1, these valves would, in practice, be combined with two additional valves controlling ports corresponding to the ports 14, 16, 18, and 20 of Fig. 1. These additional valves might be operated by connections such as those indicated at 46, 47, 48 in Fig. 2, or by an arrangement duplicating the one illustrated by Fig. 3, that is, there might be another shaft like 12' with its own set of wheels such as 51, 52, 53 and crank pins to operate such additional valves.

Fig. 4 shows an arrangement of the same general character as the one described with reference to Fig. 3, but the wheels 52' and 53' which are driven by the wheel 51 on the shaft 12', instead of being provided with crank pins, have cam grooves such as the one shown at 61, 66, 67 on the lower surface of the respective wheel, such groove comprising two concentric or dwell portions 66, 67 of different radii located on opposite sides of their center, which coincides with the axis of the wheel 52' or 53' respectively. These two dwell portions are connected by cam portions proper 61. The valve 21'' sliding along the guides 68 is shown as provided with a tongue 63 from which a pin 64 projects upwardly into the cam groove 61, 66, 67. As in the form illustrated by Fig. 3, the wheels 51, 52', 53' and their operative connections with the respective slide valves are located in the same chamber or compartment (28), and the remarks made with reference to Fig. 3 as regards the provision of additional valves to govern ports such as 14, 16, 18, and 20, and as regards the operation of such additional valves, will also apply to Fig. 4. Inasmuch as the timing of the valve or valves controlled by the wheels 52 (Fig. 3) and 52' (Fig. 4) is to be different from the timing of the valve or valves controlled by the wheels 53 and 53' respectively, the crank pins 54, 59 in one case, and the cam grooves 61, 66, 67 in the other case, are set differently, the pins 54, 59 being in positions at 90° from each other, and the cam groove of the wheel 52' being in a posi-

tion at 90° from the position of the cam groove of the wheel 53'. Thus, if in Fig. 3 we draw a line from the center of pin 54 to the center of wheel 52, this line will be perpendicular to a line connecting the center of pin 59 with the center of wheel 53, and a similar relation will obtain, in Fig. 4, as regards the position of the cam grooves on the wheels 52' and 53'. At 68 I have indicated, in Figs. 3 and 4, suitable guides for the valves 21', 21^a, and 21''.

With reference to the connection 47 shown in Figs. 1 and 2 (and available, as set forth, in conjunction with the forms of my invention illustrated by Figs. 3 and 4), it will be understood that it extends beneath the partition 1, that is to say, in that compartment or chamber of the casing which contains the measuring chambers. It will be understood that the horizontal partition 1 divides the casing into an upper chamber (subdivided by the vertical partition 27 into the inlet compartment 28 and the outlet compartment 29) and the lower chamber which, as just stated, contains the measuring chambers 2, 3, 4, and 5. My invention is applicable to meters of the type shown in my Letters Patent of the United States, No. 1,758,083 dated May 13, 1930, and to other gas meters as well. By connecting the actuating shaft directly with only one of a pair of valves, and actuating the other valve of such pair indirectly, by a connection coming from said directly operated valve, I avoid the necessity for passing one of the valve-actuating members through a partition such as 27. In my said earlier application, one of the connections from the actuating shaft 12 to one valve of each pair extends through the partition 27, and a special packing is required at this point.

Various modifications may be made without departing from the nature of my invention as set forth in the appended claims.

45 I claim:

1. In a device of the class described, a casing having a partition dividing it into an upper chamber and a lower chamber, and another partition dividing said upper chamber into an inlet compartment and an outlet compartment, each provided with a port, valves controlling said ports, mechanism, located in one of said compartments, for the direct actuation of the valve thereof, and an operative connection extending from said valve to the other valve, through said lower chamber and clear of the partition which separates said compartments.

2. A device according to claim 1, in which 60 the valves move rectilinearly and are connected by a rod.

3. In a device of the class described, a casing having a partition dividing it into an inlet compartment and an outlet compartment, 65 each provided with a port, valves controlling

said ports, mechanism, located in one of said compartments, for the direct actuation of the valve thereof, and an operative connection extending from said valve to the other valve, exteriorly of said compartments and clear 70 of said partition.

4. In a device of the class described, an inlet compartment and an outlet compartment, each provided with a port, slide valves movable in the same direction and controlling 75 said ports, mechanism, located in one of said compartments, for the direct actuation of the valve thereof, and a rod extending from said valve in the direction of the path of the valve and connected with the other valve to 80 actuate the latter, said rod being arranged exteriorly of the compartment in which said direct actuation mechanism is located.

5. In a device of the class described, a casing having a partition dividing it into an upper chamber and a lower chamber, and another partition dividing said upper chamber into an inlet compartment and an outlet compartment, each provided with a port, valves controlling said ports, a measuring 85 chamber located in said lower chamber and communicating with said compartments through said ports when the respective valves are open, mechanism, located in one of said compartments, for the direct actuation of the valve thereof, and an operative connection extending from said valve to the other valve, through said measuring chamber and clear of the partition which separates said compartments.

In testimony whereof I have signed this specification.

GEORG MEYER.
